US0D1083984S

(12) **United States Design Patent** (10) **Patent No.:** **US D1,083,984 S**
(45) **Date of Patent:** **** Jul. 15, 2025**

(54) **DISPLAY SCREEN OR PORTION THEREOF WITH GRAPHICAL USER INTERFACE**

(71) Applicant: **Matrix Absence Management, Inc.**,
Phoenix, AZ (US)

(72) Inventor: **Gordon Smith**, Phoenix, AZ (US)

(73) Assignee: **Matrix Absence Management, Inc.**,
Phoenix, AZ (US)

(**) Term: **15 Years**

(21) Appl. No.: **29/909,751**

(22) Filed: **Aug. 10, 2023**

Related U.S. Application Data

(63) Continuation of application No. 17/402,966, filed on Aug. 16, 2021, which is a continuation of application No. 16/858,462, filed on Apr. 24, 2020, now Pat. No. 11,093,902.

(57) **CLAIM**

The ornamental design for a display screen or portion thereof with graphical user interface as shown and described.

DESCRIPTION

The FIGURE is a front view of a display screen or portion thereof with graphical user interface, in which the contrasting portions of the graphical user interface are shown in a slanted line hatching pattern and a horizontal dashed line hatching pattern.

The outermost broken lines illustrate a display screen or portion thereof, which form no part of the claim design. The
